[57] **CLAIM**

The ornamental design for a lotto number selector, as shown and described.

DESCRIPTION

FIG. 1 is a front elevation view of a lotto number selector showing our new design;

FIG. 2 is a top plan view thereof;

FIG. 3 is a bottom plan view thereof; and,

FIG. 4 is a side elevation view thereof.

The undisclosed rear view is planar and unornamented except for the round pin that is identical to the front center pin.

FIG. 1

FIG. 4

FIG. 2

FIG. 3
